Atty.

UNITED STATES PATENT OFFICE.

HENRY JAMES STEWART CROSS, OF TORONTO, ONTARIO, CANADA.

BRUSH.

Application filed January 15, 1925. Serial No. 2,627.

To all whom it may concern:

Be it known that I, HENRY JAMES STEWART CROSS, a subject of the King of Great Britain, residing in the city of Toronto, county of York, Province of Ontario, Canada, have invented certain new and useful Improvements in Brushes, of which the following is a specification.

My invention relates to improvements in 10 brushes, and relates more particularly to brushes used in polishing hardwood floors, and the object of the invention is to provide a cheaply made yet efficient brush for the purpose set forth whereby the uneven surfaces of a floor can be as readily polished as the even surfaces, and in the following 15 specification I shall illustrate and describe my invention, and what I claim as new will be set forth in the claims forming part of 20 this specification.

Fig. 1 is a plan view of my brush. Fig. 2 is a vertical cross section on the line 2—2, Fig. 1, and Figs. 3 and 4 are longitudinal vertical sections on the lines 3—3, and 4—4, 25 respectively, Fig. 1.

In the drawings, like characters of reference refer to the same parts.

It is very necessary to provide a brush, 30 flexible in character which will polish the uneven as well as the even surfaces of a floor, and in order to produce a commercial article for the purpose set forth, it is absolutely essential that this article be cheap to manufacture.

35 2 and 3 are brushes which are held in fixed relative relationship by means of plates 4 which fit against the ends of these brushes, and are suitably secured thereto as by nails 5. The brushes 2 and 3 are spaced 40 apart, and located in the space between these brushes is a brush 6 which is free to move up and down according to the state of the surface of the floor. Should the brush be passed over a portion of the floor which 45 is below the general surface thereof, it will move down thus keeping its bristles in contact with the depressed or lower portion of the floor surface and thus effect polishing of same. This position of the brush 6 is shown clearly in Fig. 4.

In order to hold the brush 6 in co-operative relationship in respect of the brushes 2 and 3, the plates 4 are provided with upper and lower flanges 7. Each end of the

brush 6 is cut away so as to provide shoulders 8, and each of these shoulders is shallower than the space separating the flanges 7, consequently room is allowed for the vertical movement of the brush 6.

The lowermost flanges 7 of course limit 60 the downward movement of the brush 6 and also prevent this brush from dropping out of place between the brushes 2 and 3 when the article is lifted from off the floor.

Each brush is weighted after any suitable 65 manner to provide for the necessary pressure, and it will be obvious that this weighting of the brushes may be carried out in various ways without departing from the spirit of my invention.

I prefer however to attach to the top of 70 each brush 2 and 3 a metal bar 9 co-extensive in length and width with each brush. Also attached to the top side of the brush 6 is a metal plate or bar 10. This plate or bar 75 10 has sufficient clearance with the top flanges 7 and the inner sides of the brushes 2 and 3 to allow for free action of the brush 6: and it will be also understood that the brush 6 has sufficient clearance at each end 80 with the plates 4, and at each side with the brushes 2 and 3 to allow for its free action.

Lugs or ears 11 are carried by the plates or bars 9 so as to permit any suitable handle (not shown) to be associated with the 85 article.

This article is efficient in action, and the construction disclosed permits of the replacement of any worn portion.

Although the flanges 7 are shown as overlapping the ends of the brushes 2 and 3, at their top and bottom sides, still these flanges need not necessarily extend beyond the width of the brush 6, because their function is to limit the vertical movement of the 95 brush 6.

What I claim as my invention is:

1. A polishing device comprising two weighted brushes laterally spaced apart; a movable weighted brush located in the space 100 between said first-mentioned brushes, means holding said first-mentioned brushes in fixed spaced relationship and bridging the space therebetween at each end thereof, and means carried by said holding means and co-acting with the ends of said movable brush to permit of the free limited vertical movement thereof, for the purpose specified.

2. A polishing device comprising two weighted brushes laterally spaced apart; a plate attached to each end of each of the said brushes to couple them together, said plate being provided with top and bottom flanges which project into the space between said brushes; a weighted movable brush lo-

cated in the space between said first-mentioned brushes, and provided at each end with a projecting shoulder, the said flanges 10 co-operating with the shoulders of said movable brush to limit vertical movement thereof.

HENRY JAMES STEWART CROSS.
